UNITED STATES PATENT OFFICE

ARTHUR ATWATER KENT, OF ARDMORE, AND RUSSELL T. KINGSFORD, OF WYNCOTE, PENNSYLVANIA; SAID KINGSFORD ASSIGNOR TO SAID ARTHUR ATWATER KENT

RADIO SPEAKER

Application filed January 31, 1928. Serial No. 250,789.

Our invention relates to telephonic apparatus, and particularly to amplifying telephones, loud speakers or radio speakers, utilized in connection with radio receiving apparatus.

In accordance with our invention, a sound reproducing diaphragm of relatively large area, and more particularly conical in shape, is disposed within a housing or casing, the walls of which on opposite sides of the diaphragm are provided with apertures, the area of which in a wall is less than the effective area of the diaphragm, as the base area of a cone; more particularly, the periphery of a diaphragm, particularly when entirely free and unsupported, and preferably embraced by a member, as of felt attached thereto, vibrates in proximity to but out of contact with flange structure extending along the diaphragm adjacent its periphery and preferably on both sides thereof; which features of construction, singly or in combination improve the sound reproducing characteristic particularly at the lower range of audible frequencies.

More specifically, the diaphragm is supported within the housing, preferably of metal, as by electromagnetic actuating mechanism secured to a wall thereof, with its apex directed toward said wall, the apertures through which are preferably covered or partially closed by foraminous material, as fabric or the like, and with one face of the diaphragm adjacent its periphery spaced from a flange constituting an inwardly directed rim of the housing, and preferably with its opposite face adjacent its periphery spaced from a flanged member engaging, supported by and spaced from the first flange, and which more particularly is provided with grille structure or constitutes a part of the second apertured wall.

Our invention further resides in features of construction, arrangement and combination hereinafter described and claimed.

For an understanding of one of the forms of our invention, reference is to be had to the accompanying drawings in which:

Fig. 1 is an elevational view of a device embodying our invention.

Fig. 2 is a side elevational view in section taken on line 2—2 of Fig. 1.

Fig. 3 is a plan elevational view in section taken on line 3—3 of Fig. 1.

Fig. 4 is a detailed view, on an enlarged scale, showing the disposition of the rim of a conical diaphragm utilized in my loud speaking device.

Fig. 5 is a detailed view in plan, on an enlarged scale, of electromagnetic apparatus employed in the device.

Fig. 6 is a detail view taken on line 6—6 of Fig. 5 and disclosing the mode of mounting the speaker diaphragm on the electromagnetic driving mechanism.

Fig. 7 is a detailed view taken on line 7—7 of Fig. 6.

Referring to the drawings, the base member 1 is a casting, preferably hollow, of suitable composition, as iron, and mass provided with soft or resilient pads 2, as of felt, suitably affixed as by adhesive to its lower surface. The top face or edge of the base member is shaped to conform with the outline of a portion of a casing or housing member 3, preferably of sheet metal, as steel, and is suitably secured thereto as by bolts 4 which pass into the interior of the housing and on which are threaded nuts 5 firmly to clamp the housing and base members. The casing or housing member 3 is a relatively shallow tubular member of large diameter and preferably cylindrical, particularly when utilized with a diaphragm of the configuration hereinafter described. The left, open end of the housing, as viewed in Fig. 2, and referred to as the front of the device is provided with an inwardly directed, curved flange 6 having a shoulder portion 7 of slightly smaller diameter than, and adjacent the main body of the housing. Through the opposite or rear face 3a of the housing are apertures 8, preferably circular and of substantial diameter, and having inwardly turned flanges 9 pressed from the sheet comprising the housing.

Across each of the apertures is stretched fabric 10, or equivalent, of suitably fine mesh, maintained in position by a ring 11, as of fiber, or rubber, clamping the portion of the fabric extending beyond the periphery of the aper-

ture firmly into contact with the outside of the flange 9.

Within a centrally disposed recessed portion 12 of the rear face of the housing is positioned electromagnetic driving mechanism 13 secured thereto as by bolts 14, 14 extending to the exterior of the housing to threadably engage cap nuts 15, 15.

The electromagnetic mechanism is of the character described and claimed in co-pending Kingsford application Serial No. 155,158, filed December 16, 1926, and comprises a pair of permanently magnetized yokes or frames 16, 16, preferably duplicate in character and each cut away or recessed interiorly thereof to define a substantially rectangular opening. Disposed between the yokes 16, 16 is the vibratile member reed or armature 17 on either side of which, adjacent one end thereof, is disposed a washer 18, preferably of non-magnetic material, as brass or the like through which and the perforated end of reed 17 extends a bolt 19 or the like for holding the parts in assembled relation. To the end that the yokes 16, 16 may be held in parallel relation or substantially so, at the end thereof removed from the bolt 19, there is provided the spacing washer 20, preferably of non-magnetic material as brass or the like and whose thickness corresponds substantially with the combined thickness of reed 17 and washers 18. Passing through this end of frames 16, 16 and washer 20 is the bolt 21, preferably corresponding with bolt 19.

Secured between the yokes or frames 16, 16 by the bolts or screws 14 are the inwardly directed pole pieces 22 each of which is bifurcated to form the spaced pole piece extensions or end portions 23 and 24. The extensions 23 are offset in opposite directions and disposed in superposed or spaced relation for the reception of the free end of reed 17. The pole piece extensions 24 are not offset, as are the extensions 23, but are extended in suitable close relation to the edges of reed 17 to thereby provide a shunt path for the magnetic flux threading through said reed by virtue of the coil or winding 25 associated therewith and which is traversed by fluctuating voice- or sound-representing current, such as exists, for example, in the anode circuit of a detector or audio frequency amplifier as utilized commonly in radio receiving circuits. The coil 25 is supported on the pole pieces by members 26 directly in contact with the inner bore of the coil, or with a strip or layer 27 of paper, cloth or the like interposed between. The terminals 28 and 28a of the coil 25 are connected to binding posts 29 and 29a mounted in spaced relation on a member or plate 30 preferably held in place on a yoke or frame 16 by the aforesaid bolt or screw 21. The plate 30 may be formed of suitable insulating material as a phenol condensation product, or hard rubber, but preferably comprises

a fabric as linen, or canvas impregnated in a phenol condensation product. As hereinbefore described, the reed 17 is clamped between the yokes 16, 16 by the bolt 19. Between this screw and the coil C and preferably extending through ears 31 of yokes 16, 16 are the members or screws 32 and 33 each of which at its end engages an opposite face of the reed 17. The screws 32 and 33 are adjustable to vary the dimensions of the air gaps between the free end of the reed 17 and the adjacent faces of pole extensions 23.

Member 34 may be secured to reed 17 in any suitable manner, preferably, however, as illustrated by riveting a block 35 to the reed and riveting the block and member 34 to each other. The diaphragm 36 preferably conical, and of China wood, parchment or the like, at its apex is provided with a circular opening faced by the headed or turned portion of a conical member 37 of suitable material as aluminum or soft steel, disposed exteriorly upon the diaphragm 36. Disposed exteriorly thereof is the conical facing member or washer 38, preferably of hard steel or the like. As shown, the inner portion of member 37 is turned or headed and encompasses the adjacent edges of the diaphragm 36 and member 38. Resting on the exposed face of member 38 are the angularly disposed portions of a supporting member or bracket 39 of steel or other rigid material comprising two legs which converge to form a pocket receiving the end of member 34. Passing through aligned perforations in the pocketed portion of bracket 39 and the end of member 34 is a bolt or the like 40. The angular portions of the bracket 39 and members 37 and 38 may be rigidly united with the diaphragm 36 by utilizing a plurality of rivets or the like 40 each headed on opposite sides of the diaphragm.

The member 34 is of spring steel as phosphor bronze or the like, and due to its flexibility bends in a plane extending at right angles longitudinally of the yokes 16, 16 and as a result, due to the inertia of the cone, little or no transverse bodily movement is imparted thereto due to the pivotal movement of reed 17. To prevent contact between the flexible member 34 and the cone intermediate its ends, and to dampen transverse vibration of the member there is provided a buffer ring 34', of rubber or the like. The cone as described and claimed in co-pending Kent application Serial No. 32,875, filed May 26, 1925 is unrestrained throughout and free to vibrate at its periphery, the driving member 34 constituting the sole support therefor and relatively non-flexible in the direction coinciding with the gravitational plane of the cone to carry its weight without flexing or bending, for example, the member may be of substantially greater breadth than thickness.

The cone 36 and its electromagnetic actuator

ating mechanism 13 when assembled and disposed as a unit within the housing member 3, are substantially completely enclosed thereby, the base of the cone, however, projects 5 slightly outside of the housing member, the periphery of the cone comprising a turned-back or stiffening portion 41 of diameter suitably greater than that of the opening in housing member 3 defined by flange 6.

10 The shoulder 7 of flange 6 is engaged by a detachable member 42 the edge of which abuts the housing approximately at its junction with the flange and is secured thereto as by screws 43. The diameter of the flange 6 at the shoulder portion 7 is reduced to permit 15 the outer surface of the housing member 3 and that of detachable member 42 to present a single, substantially unbroken surface when assembled to form the entire or complete housing for the diaphragm 36 and its actuating mechanism.

The periphery of the diaphragm 36 secured to and preferably embraced by a member 44, of felt or equivalent vibrates freely 25 within the region or space between the flange 6 and rim 45 of detachable member 42. The distances between adjacent faces of the flange and rim, and of the felt member 44 are sufficiently great to prevent actual contact, however slight, therebetween under all 30 operating conditions. Within the range afforded by screws 32 and 33 for varying the position of reed 17 with respect to pole pieces 23, 23, it is not possible to adjust the position 35 of cone 36 to effect or permit contact thereof with either the rim 45 or flange 6.

An open grille structure 46, as for example, of the character disclosed and claimed in Kingsford Design Patent No. 73,261, issued 40 August 16, 1927, is carried by and preferably integral with the detachable structure 42 to constitute a second apertured wall of the assembled housing within which the cone 36 is completely disposed.

45 The features of construction described including the apertured housing member 3 and the guard ring 42 and associated grille 46, singly or in combination with each other, and particularly in combination with the flange 6 and felted edge 41 of the diaphragm improve 50 the sound-reproducing properties of the device particularly at the lower ranges of audio frequencies.

55 The term "free-edge" or its equivalent as applied to a sound-reproducing diaphragm in the above description and appended claims, is defined as descriptive solely of a diaphragm whose periphery is to no degree 60 in contact with and to no degree supported by any member other than the cone itself.

Further the expression "diaphragm of large area" as employed herein, is definitive of a diaphragm having a diameter of six 65 inches or more, or equivalent.

What we claim as novel and desire to protect by Letters Patent is:

1. A housing for a conical sound-reproducing diaphragm of large area having a freely vibratory periphery, comprising walls on opposite sides of said diaphragm, each having substantial area of opening therethrough in a plane parallel to the base of said conical diaphragm. 70

2. A housing for a sound-reproducing diaphragm of large area, comprising walls on opposite sides of said diaphragm, each wall having openings therethrough whose combined area is less than the effective area of said diaphragm in a plane normal to its axis 80 of movement. 75

3. A housing for a sound-reproducing diaphragm of large area, comprising walls on opposite sides of said diaphragm, each wall having openings therethrough whose combined area is less than the effective area of said diaphragm in a plane normal to its axis 85 of movement, and structure of foraminous material partially closing the openings of at least one of said walls. 90

4. A housing for a conical sound-reproducing diaphragm of large area, comprising walls on opposite sides of said diaphragm, each wall having openings therethrough whose combined area is less than the base area 95 of said conical diaphragm in a plane normal to its axis. 95

5. A housing for a conical sound-reproducing diaphragm of large area having a freely vibratory periphery spaced therefrom, comprising walls on opposite sides of said diaphragm, each wall having openings therethrough whose combined area is less than the base area of said conical diaphragm. 100

6. A housing for a conical sound-reproducing diaphragm of large area having a freely vibratory periphery spaced therefrom, comprising walls on opposite sides of said diaphragm, each wall having openings therethrough whose combined area is less than the base area of said conical diaphragm, and structure of foraminous material partially closing the openings of at least one of said walls. 105

7. Housing structure for a conical sound-reproducing diaphragm of large area and its actuating mechanism, comprising metal wall structure presented to the convex side of and enclosing said diaphragm, said wall structure having substantial area of opening therethrough, and a metal enclosure for said actuating mechanism projecting outwardly from said wall structure in the axis of movement of said diaphragm. 110

8. Housing structure for a conical sound-reproducing diaphragm and its actuating mechanism, comprising metal wall structure presented to the convex side of and enclosing said diaphragm, and a metal enclosure for said actuating mechanism projecting out- 115

wardly from said wall substantially centrally thereof in the axis of movement of said diaphragm, said wall structure having apertures circumferentially spaced about said enclosure, the combined area of said apertures being smaller than the base area of said conical diaphragm.

ARTHUR ATWATER KENT.
RUSSELL T. KINGSFORD.
